UNITED STATES PATENT OFFICE.

EDWARD J. DOLAN, OF PHILADELPHIA, PENNSYLVANIA.

SEAMING-PRESS.

SPECIFICATION forming part of Letters Patent No. 286,283, dated October 9, 1883.

Application filed June 27, 1883. (No model.)

To all whom it may concern:

Be it known that I, EDWARD J. DOLAN, of the city of Philadelphia, county of Philadelphia, and State of Pennsylvania, have invented 5 an Improvement in Seaming-Presses, of which the following is a specification.

My invention has reference to machines for making tin-can bodies or seaming-presses; and it consists in certain improvements in mechanism for forming the seam, all of which is 10 fully set forth in the following specification and shown in the accompanying drawings, which form part thereof.

The object of my invention is to form a seam 15 on tin-can bodies or sheet metal generally by first creasing the lapped edges and bending the bent portion of seam obliquely over, so that when crushed down by the hammer a perfect seam is the result.

20 In the drawings, Figure 1 is a side elevation of a seaming-press embodying my improvements. Fig. 2 is a vertical section of same on line α α . Fig. 3 is a cross-section on same line of the dies, showing the first step in forming the seam. Fig. 4 is a similar view, showing the dies closed and the second step; and Fig. 5 shows the seam crushed down by the hammer.

A is the frame of the machine.

25 B is the forming or receiving die.

C is the seaming-die plunger, and works in guide A', being allowed lateral play, but kept against one face of the guide A', and leaving the space A² on the other by a block, F, and 30 spring G, whose tension may be regulated by a plate, H, and screw I. This plunger C is reciprocated by a lever, E, which is connected therewith by links e and pin e', the said plunger having lateral play upon said pin e'. The 35 free end of lever E is held down by a spring, E', and may be oscillated to actuate the plunger by rod E' and treadle E². The plunger C carries the seaming-die D, which is formed in the usual manner, except that the A-shaped slot 40 or groove D², formed between the body and knife-edge D', is made oblique, and is made to fit upon the oblique prong R, formed on the receiving-die B.

J is a loose guide-bar, which slides freely in 45 the hole J' in the plunger C, the said guide-bar always remaining stationary while the plunger and die reciprocate.

B' is a tension or take-up bar, and is held to

the die B by screws b', and works in a slot, B², and is pressed outward by springs b². 55

K is a discharging-ring, and encircles the die B, being provided with fingers k, which enter grooves b, to insure the tin being pushed from under die D. This ring K is reciprocated by rods K' and springs K², which rods are 60 actuated by bell-crank lever L, which has one arm resting against the end of said rods K', or a cross-bar secured thereto. This lever L is reciprocated by a pivoted pawl, L', secured to the rod E' or actuated thereby. The upward 65 movement of rod E' simply actuates the pawl L to no effect; but the downward movement thereto reciprocates the ring K.

M is a guide under which the sheet metal is pushed, and tends to keep it in shape during 70 the act of forming the seam, and may be adjusted to and from the die B by rod m and nuts m'. The die B is prolonged to support the crimped can-body to be hammered, and may be provided with a groove, T, to insure 75 the proper bending of the crimp to form a compact and perfect seam.

N is the hammer, and is secured to the bottom of a vertically-reciprocating rod, N', guided in bearings n, and provided on the top with a 80 head, N². This hammer is pressed downward by springs N². It is lifted by a lever, O, provided on its free end with a pawl, O', kept in working position by a spring, O², which pawl catches under the head N² of rod N'. The 85 other end of lever O is oscillated by a rod, P, and treadle P'.

In machines for making small cans the die B is so reduced in diameter that it is desirable 90 to support it against the force of the hammer N by suitable auxiliary means, which support said die B only when the hammer strikes it, the said support being entirely clear of the die B when crimping the seam and inserting the tin or removing the finished can-body. To do 95 this I pivot an arm, S, to a shaft, S', supported in bearing S², the said shaft being rocked by a crank, S³, which is pulled up by a spring, S⁴, and down by a rod, S⁵, hinged to the treadle P' for operating the hammer N, the said rod S⁵ 100 being adapted to slide loosely in the crank S³, and provided with a head, S⁶. When the treadle P' is pressed down, the hammer is slightly raised. Then the head S⁶ of rod S⁵ 105 catches on the crank S³ and pulls it down, throwing in the arm S under the die B just as

the hammer is freed and falls. The parts then assume their original positions, when the pressure is removed from the treadle. This support mechanism may be made in various ways, and I therefore do not limit myself to the details of construction.

The operation is as follows: The sheet-metal strip to form the can-body is bent around the die B, the ends lapped and passed under guides 10 M and J, and the outer free end brought against the guide J, as shown in Fig. 3. The treadle E² is then pressed down. This lowers the die D, crimping the lapped sheet metal, and toward the completion of the downward movement 15 the oblique grooves in the dies cause the die D and its plunger C to move laterally, closing the space A² and opening the space C', compressing spring G, and thereby crimping the sheet metal with an oblique bent part, as 20 shown in Fig. 4. The spring E³ then comes into play, raising die D, and the rod E' is pulled down, which action pushes forward ring K, causing the crimped can-body Q to be pushed forward under the hammer N, which 25 has been raised, the tension-bar B' keeping the crimped ends clamped firmly. The treadle P' is then pushed down as far as possible, or until the pawl of lever O slips from under head N², when the springs N³ force the hammer down 30 upon the oblique crimp, causing it to bend down in the right direction and insuring perfect seams. The main novelty in this invention lies in the oblique formation of the seaming-crimp, so that it must bend in the right 35 direction when struck by the hammer.

Flat sheet metal may also be joined by this machine; but in place of a round die, B, a flat table would be required.

I do not limit myself to the exact construction shown, as it may be modified in various ways without departing from my invention.

I am aware of the patent to Gordon, No. 222,691, of 1879, and do not claim anything therein set forth or shown.

Having now described my invention, what I claim as new, and desire to secure by Letters Patent, is—

1. A sheet-metal-seaming press provided with two dies having oblique crimping-faces, 50 said dies being adapted to form a crimp to the lapped edges of the sheet metal, both faces of which crimp are oblique, to the end that when the said crimp is struck with a hammer it is caused to bend in the right direction, and 55 mechanism to operate said dies, substantially as and for the purpose specified.

2. In a sheet-metal-seaming press, the combination of a stationary or fixed die with a vertically and laterally reciprocating crimping-die, and means to operate said die, substantially as and for the purpose specified.

3. A sheet-metal-seaming press provided with a vertically and laterally reciprocating crimping-die, a receiving-die, and seaming-hammer, substantially as and for the purpose specified.

4. A sheet-metal-seaming press provided

with a vertically and laterally reciprocating crimping-die, a receiving-die and seaming-hammer, and suitable guides to control the feed and delivery of the sheet metal, substantially as and for the purpose specified.

5. A sheet-metal-seaming press provided with a vertically and laterally reciprocating crimping-die, a receiving-die and seaming-hammer, and a discharging device by which the crimped sheet metal is automatically fed under the hammer, substantially as and for the purpose specified.

6. The combination of die B, having oblique knife-edge R, with die D, having oblique groove D² and knife-edge D', substantially as and for the purpose specified.

7. The combination of die B, having oblique knife-edge R, with die D, having oblique groove D², knife-edge D', and means to reciprocate said die D vertically and laterally, substantially as and for the purpose specified.

8. The combination of guide A', plunger C, die D, block F, and spring G, substantially as and for the purpose specified.

9. The combination of guide A', plunger C, die D, block F, spring G, plate H, and bolt I, substantially as and for the purpose specified.

10. The combination of guide A', plunger C, die D, die B, loose guide J, and rigid guide M, substantially as and for the purpose specified.

11. The combination of guide A', plunger C, die D, block F, spring G, die B, and take-up bar B', substantially as and for the purpose specified.

12. The combination of die B, die D, means to reciprocate said die D vertically, and also give it lateral motion, hammer N, rod N', spring N³, head N², lever O, having spring-pawl O', rod P, and treadle P', substantially as and for the purpose specified.

13. The combination of die B, discharging-ring K, means to reciprocate said ring, die D, means to reciprocate said die D vertically, and also give it lateral motion, hammer N, rod N', spring N³, head N², lever O, having pawl O', rod P, and treadle P', substantially as and for the purpose specified.

14. The combination of a tin-can-body-receiving die, B, a hammer to strike said die, a movable support for said die, mechanism to actuate said hammer and support, and so timed that the support is automatically placed under said die just as the hammer falls, substantially as and for the purpose specified.

15. The combination of hammer N, die B, and pivoted support S, substantially as and for the purpose specified.

16. The combination of hammer N, die B, pivoted support S, shaft S', crank S³, rod S⁵, having head S⁶, spring S⁴, and treadle S', substantially as and for the purpose specified.

In testimony of which invention I hereunto set my hand.

EDWARD J. DOLAN.
